UNITED STATES PATENT OFFICE.

GEORGE BEDWELL AND PERCY WEBB, OF SACRAMENTO, CALIFORNIA.

REVOLVING SCOOP OR DITCH CLEANER.

Application filed June 14, 1923. Serial No. 645,362.

To all whom it may concern:

Be it known that we, GEORGE BEDWELL and PERCY WEBB, citizens of the United States of America, residing at Sacramento, 5 in the county of Sacramento and State of California, have invented certain new and useful Improvements in Revolving Scoops or Ditch Cleaners, of which the following is a specification.

10 This invention relates to new and useful improvements in revolving scoops or ditch cleaners.

An important object of this invention is to provide a revolving scoop which is especially suitable for cleaning out irrigation ditches previously formed and for checking or turning the course of water at any time that it is deemed advisable.

Other objects and advantages of the invention will be apparent during the course of the following description.

In the accompanying drawing forming a part of this specification and in which like numerals are employed to designate like 25 parts throughout the same,

Figure 1 is a side elevational view of the revolving scoop embodying this invention,

Figure 2 is a vertical sectional view partly in elevation, of the revolving scoop shown 30 in Fig. 1,

Figure 3 is a detail elevational view of a locking means employed for retaining the revolving scoop in one of its operative positions and taken on line III—III of Fig. 2, and

Figure 4 is a fragmentary view showing a longitudinal section of the dual scoop embodying this invention and taken upon line IV—IV of Fig. 1.

40 In the drawing, wherein for the purpose of illustration is shown a preferred embodiment of this invention, the numeral 5 designates the beam which is provided with a hook formation 6 at its forward end to

45 which is secured suitable means for drawing the scoop during operation of the same. The rear portion of the beam 5 is formed from two plates that diverge outwardly, as at 7 with their extreme outer ends bent

50 downwardly, as at 8 for the purpose of receiving the fulcrum bar 9 upon which the dual scoop element 10 is pivotally mounted. Suitably secured to the rear ends of the diverging portions 7 of the beam 5 are handle members 11 that are employed for steering the device.

For the purpose of retaining the dual scoop member 10 in either of its operative positions, a disk 12 is secured to this element 10 by means of the bolts or rivets 13 60 as best shown in Figs. 3 and 4. This disk 12 is provided with diametrically opposed notches or recesses 14 that are adapted for selectively receiving the perpendicular sliding bolt 15 which is carried by one of the 65 depending arms 8 forming a portion of the beam member 5. This depending arm 8 is provided with a pair of spaced guiding straps 16 for the purpose of securing this bolt member 15 thereto. Rigidly connected 70 to the bolt 15 is a washer member 17 that is adapted for being engaged by the lower end of a tension spring 18 which bears at its upper end against the upper strap member 16 carried by the depending arm 8. It 75 will be seen that this spring 18 will force the bolt 15 downwardly to engage one of the notches or recesses 14 when the same is moved into vertical alinement with said bolt. For the purpose of actuating this 80 bolt 15, a supporting arm 19 is secured to a portion of the beam member 5 and is adapted for pivotally carrying the bell crank member 20 at its outer end which is connected by means of a link 21 to the upper end of the said bolt 15. The opposite arm of this bell crank member 20 is connected to a rod 22 that passes upwardly in parallel with one of the handle members 11 for the purpose of being connected to 85 the hand grip lever 23 which is mounted at the upper end of this handle member 11. It will be seen that when this hand grip lever 23 is actuated, the bolt 15 will be drawn upwardly against the tension of the 90 spring 18 for the purpose of removing its outer end from the recess 14 in the disk 12 that it was then occupying.

The operation of the device is as follows:—

When the user desires to clean out ditches, preferably used for irrigation purposes, one of the dual scoops 10 will be facing forwardly as shown in Fig. 1. By causing the scoop to be drawn along the walls of the 105 said ditch, a desired amount of excess dirt will be collected therewithin and carried along the ditch. When the farmer desires to check the flow of water into any particular portion of a ditch, he will run the said 110 scoop through a portion of the section in question until he has collected a desired

amount of dirt in the scoop and has reached the mouth of this particular ditch, or the entrance thereto from a main supply ditch, he will then actuate the lever 23 for the purpose of removing the bolt 15 from its then engaged notch 14 whereupon the dual scoop 10 will be allowed to rotate as shown in arrow lines in Fig. 1 for the purpose of dumping the collected dirt at the mouth of this ditch. The depositing of this scoopful of dirt will naturally check or turn aside the course of water at that point.

It is to be understood that we do not desire to limit the adaptation of this scoop for irrigation purposes. Persons skilled in the art will readily see that this device may be put to many different uses.

It is to be understood that the form of this invention herewith shown and described 20 is to be taken as the preferred example of the same, and that various changes in the

shape, size, and arrangement of parts may be resorted to without departing from the spirit of the invention or the scope of the subjoined claim.

Having thus described the invention, we claim:—

In a device of the kind described, a draft beam having its rear portion bifurcated and turned down to form a pair of laterally spaced legs, a shaft connecting the lower ends of said legs, a dual scoop rotatably mounted on said shaft, and consisting of a cylindrical member having a partition intermediate its ends, opposite side portions of said member being removed on opposite sides of said partition, and means to hold said scoop releasably in selected positions.

In testimony whereof we affix our signatures.

GEORGE BEDWELL.
PERCY WEBB.
